Primary Examiner — Patricia Palasik(74) *Attorney, Agent, or Firm* — Kilpatrick Townsend & Stockton LLP**CLAIM**

The ornamental design for a wire feeding apparatus for welding, as shown and described.

DESCRIPTION

FIG. 1 is a front, top, and right side perspective view of a wire feeding apparatus for welding showing our new design; FIG. 2 is a rear, top, and left side perspective view thereof; FIG. 3 is a front view thereof; FIG. 4 is a rear view thereof; FIG. 5 is a top plan view thereof; FIG. 6 is a bottom plan view thereof; FIG. 7 is a right side view thereof; and, FIG. 8 is a left side view thereof.

The oblique line shading shown in the drawings indicates a transparent or translucent surface. Internal structure of the transparent or translucent surface is omitted. No claim is made to any elements inside the transparent or translucent surface.

1 Claim, 8 Drawing Sheets---
